July 14, 1925.

1,545,491

B. GERLA

WEARING APPAREL

Filed Dec. 9, 1924

FIG. 1.

FIG. 2.

FIG. 4.

Inventor
Bernard Gerla
By H. B. Moses
Attorney

Patented July 14, 1925.

1,545,491

UNITED STATES PATENT OFFICE.

BERNARD GERLA, OF NEW YORK, N. Y.

WEARING APPAREL.

Application filed December 9, 1924. Serial No. 754,850.

To all whom it may concern:

Be it known that I, BERNARD GERLA, a citizen of the United States, residing at 1000 Whitlock Ave., in the county of Bronx and city and State of New York, have invented certain new and useful Improvements in Wearing Apparel, of which the following, taken in connection with the accompanying drawings, is a specification.

10 This invention relates to wearing apparel, such as dresses or blouses, and to collars to be used in combination therewith.

Ordinarily, dresses or blouses have collars, such collars being integral with the garment, 15 and as a result a change in the appearance of the dress or blouse is impossible except by a substantial alteration of the dress.

According to my invention, the general appearance of the dress or blouse may be 20 changed by the application thereto of an additional collar which so cooperates in appearance with the collar which forms a part of the dress or blouse, as to make the same substantially different in appearance when 25 the additional collar is applied thereto.

Referring to the drawings forming a part of this specification:

Fig. 1 is a front elevation of the upper 30 part of a dress or blouse to which the additional collar may or may not be applied, as desired;

Fig. 2 is a like view showing the additional collar applied thereto;

Fig. 3 is a cross-section on the line 3—3 of 35 Fig. 2; and

Fig. 4 is a cross-section on the line 4—4 of Fig. 2.

The dress or blouse 1 comprises the customary body part 2 which may be of suitable 40 length, that is, it may extend to or somewhat beyond the waist line only to form a waist type garment, or it may extend all the way down to include a skirt. Sleeves 3 may or may not be used, as desired; and 45 these form no substantial part of the invention.

My garment has the usual head opening 4 and this is preferably, but not necessarily, 50 V-shaped to conform with the present mode. A collar 5 is suitably attached to the neck part of the garment and it is preferably made integral with the garment in the usual manner, that is, by sewing the collar thereto, or by cutting the body of the garment 55 and the collar 5 from the same piece of goods, as one piece; or otherwise. I generally prefer that the collar 5 be of the same material as the body part of the garment. My invention, however, includes making such collar of different material than that 60 of which the body part of the garment is made, and also detachably combining the collar 5 with the garment, as well as other changes within the scope of the appended 65 claims.

Suitable ornamentation, such as tabs 6, or a ribbon bow 7, or other suitable device, or more than one ornamental device, appear or 70 appears at the upper central front part of the dress, the same having a more or less necktie-like appearance, particularly when viewed in combination with either of the collars of the dress, and especially so with the added removable collar which will be 75 later described. Such necktie-like ornamentation may or may not be integral with and form a unitary part of the collar 5; and for the purpose of illustration I have shown the tab-like members 6 as a unitary part of the collar 5, and the bow-like member stitched 80 to the body part 2.

This added removable collar 8 comprises the usual part 9 which appears outside of the garment and is visible when applied thereto and worn, and the fold-over part 10 which folds in under the neck part of the 85 dress to hold this collar in place, and is made of any suitable material, and is preferably white, and washable.

One of the main features of my invention 90 is the cutting of the material for the collar 8, and for the head opening 4, and the manufacture thereof, so that the normal shape of the collar 8 which it normally tends to assume will correspond with that 95 of the collar 5 and the head opening 4 when the added collar is applied to the garment, and as a result there will be a minimum tendency to move from its desired position.

Means may be provided for the retention 100 of the extra collar on the dress, although this is not absolutely necessary, due to the fact that the extra collar when worn is in the position which it normally tends to assume; but due to movements of the wearer, the putting on or taking off of coats or other 105 like apparel, over or from over the collar, it is possible that the extra collar may be disturbed, as is true of any collar that is attached or unattached, and for this reason 110 I prefer attaching means, such as a snap member 12 attached to the inside neck portion of the garment, at the back thereof as shown on Fig. 1, and a corresponding snap member 13 on the portion 10 of the removable collar, the two snap members 5 being of the usual type and cooperating to hold the upper back part of the removable collar in place. I prefer also to provide tab portions 14 at the two front ends of the collar, the same being elongations of 10 the fold-in part 10, and these fit in under the front part of the dress to aid in holding the added collar in place.

The garment may or may not have thereon the collar 5 as the appearance of the dress 15 may be pleasing either with or without such collar, but I prefer to have such collar, and the ornamental necktie-like device or devices described, or others having a like function, are to be used.

20 The garment having a pleasing appearance without the collar 8 has a substantially different pleasing appearance when the collar 8 is applied thereto, due to the cooperation of the ornamental or necktie-like device or devices therewith. The form of garment which I prefer includes the collar 5 integral with the dress or blouse permanently fastened thereto, and tabs 6, as shown, 25 forming a part of such collar 5 and being integral therewith, that is to say, the parts 5 and 6 are preferably one piece of goods.

I prefer to have the added collar 10 appear to the eye of an observer to be the only collar; that is, the part 9 of the added collar covers the whole of any collar present 35 on the dress, except for the ornamental, necktie-like parts.

Having described my invention, what I desire to secure by Letters Patent of the United States is:

40 1. A garment having two collars, one of said collars being attached to said garment and having a forward extension constituting a necktie-like device, and the other of said collars being detachably attachable to 45 said garment, and when attached thereto covering the first mentioned collar but exposing the necktie-like device to view.

50 2. In combination, a garment having a neck opening and a collar permanently attached to said garment at said opening and a necktie-like device adjacent the opening at the upper front central portion of the garment, and a removable collar therefor, 55 cooperating snap fastening members, one of said snap fastening members being attached to the inner side of the garment at the back of the neck opening and the other of said fastening members being attached in a corresponding position on said removable collar, the normal lines of said removable collar being the same as those of the neck opening of the dress and of the same 60 dimensions, the collar band on said removable collar being extended beyond the length of the collar to form tabs which cross each other underneath the garment at the front of the neck portion thereof, a necktie-like device independent of said removable collar and being constituted at least in part by said garment collar, said removable collar covering said garment collar but leaving the necktie-like device exposed to view when said removable collar is in normal 65 combination with said garment.

70 BERNARD GERLA.